UNITED STATES PATENT OFFICE.

DAVID SCHAEFER, OF NEW YORK, N. Y.

SAFETY-RAZOR.

1,119,122.

Specification of Letters Patent.

Patented Dec. 1, 1914.

Application filed September 2, 1913. Serial No. 787,619.

To all whom it may concern:

Be it known that I, DAVID SCHAEFER, a subject of the Czar of Russia, residing in the borough of Bronx, in the city of New York, State of New York, have made certain new and useful Improvements in Safety-Razors, of which the following description is a specification, reference being had to the accompanying drawings.

10 This invention relates to that class of razors in which the cutting blade is a separate part and is held or clamped in position by a handle which presses two plates together on the blade.

15 The object of the invention is to avoid the bending of the blade and at the same time steady the cutting blade in its position in the holder.

20 My improvements also reduce the number of parts required to hold the razor blade in place.

25 The improvements are also designed to protect the user from cutting with the corners of the blade by extending the guard plate past the ends of the blade.

30 In the drawings: Figure 1. is a front elevation of my device; Fig. 2. is an end elevation; Fig. 3. is a central cross-section of Fig. 1. Fig. 4. is a cross section through Fig. 3 on the line $x-x$ and Fig. 5. is a detached view of the clamping plate.

35 The holder of the cutting blade is made in two parts. One of which comprises the handle A integral with a guard plate B. Along each side of the guard plate B are fingers a , a set at an angle as shown in Fig. 2.

40 C is the clamping plate having a central pin b which is threaded at its free end. The plate C and pin b are integral and form one piece of the apparatus. Between the two plates B and C is clamped the cutting blade D, which projects over the fingers a . The handle A is hollow and receives a tube E introduced from the outer end. The tube E terminates in a threaded end adapted to screw into the end of the handle A and is provided with a roughened nut c . The blade D is pierced at its center with a hole through which the pin b passes. About midway in the length of the handle A is located a screw

55 nut G held in position by the tube E, which takes into a circular groove g on the outer side of it, as shown in Fig. 3. The threaded end of the stem b of the plate C is received by the threaded and knurled nut G which is readily worked with the thumb and finger. The outer or clamping plate C is flat and is made partly curved or o-gee in shape at each end. It is provided with a raised lip or retaining rim extending along the o-gee ends as shown at h . The pin b of the clamping plate C, is made integral with it or rigidly secured to it.

60 The guard plate B is of the proper length to lie within the lips or confining rims h , h , at the ends of the clamping plate C, and the guard plate B, has its ends shaped to fit exactly within the space inclosed by the rims. The razor blade should be of the exact length 65 of the guard plate and shaped at both ends to fit snugly within the rims h , h . The holding device it will be seen thus consists of two parts only; or at least only two parts which are separated when in changing the razor 70 blade. The razor blade forming a removable part held between the two plates of the holder. The handle and the guard plate do not vary their position as regards each other, but the clamping plate C is adjusted to and 75 from the guard plate by means of its central stem b , which passes through the hole in the blade. The ends of the cutting blade are shaped to fit snugly within the inclosing rims h , h , of the clamping plate C so that it 80 will not have any lateral or circular movement when the clamping plates are pressed upon it.

85 The end fingers of the guard plate B are notched and extended past the ends of the raised rims h , h , of the clamping plate C, at the points i , i , Fig. 4, so that a portion of the guard plate lies between the o-gee shaped raised rims and a portion across the ends thereof. This causes the two plates to fit 90 snugly when superimposed and projects the fingers past the ends of an intervening cutting blade.

95 Having described my improvements what I claim as my invention and desire to secure by Letters Patent is:

In a safety razor blade holder, an alter-

clamping plate having raised inclosing end
5 lips and a central stem rigidly attached
thereto said stem terminating in a threaded
end, in combination with a handle and guard
plate rigidly attached to the handle, a screw
nut G, having a circular groove g positioned

and held in the handle by a tube E and screw
cap c, substantially as shown and described.

DAVID SCHAEFER.
